UNITED STATES PATENT OFFICE.

JAMES C. WOODSON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

BAKE-OVEN-ILLUMINATING MEANS.

Application filed June 13, 1924. Serial No. 719,789.

My invention relates to heating ovens and particularly to means for illuminating the same.

The object of my invention is to provide an illuminating means for heating ovens that is so constructed and arranged that it may satisfactorily illuminate the interior of a heating oven while retaining substantial protection from the effects of the heat of the oven.

In practicing my invention, I provide a heating oven of any well known construction, having an opening in one of the oven walls. The opening is covered at its interior and exterior extremities by transparent material such as pyrax. A casing is located on the outer surface of the wall in such manner that a lamp located within the casing may direct light rays through the opening to illuminate the interior of the oven.

A door is located adjacent to the casing, and an arrangement is provided to operate a switch to close and interrupt the circuit supplying the lamp with current, upon the closing and the opening of the door.

In the single sheet of drawings,

Figure 1 is a front elevational view of a heating oven embodying my invention, parts being broken away;

Fig. 2 is a view in horizontal section of an illuminating means embodied in my invention; and

Fig. 3 is a view in vertical section thereof.

A heating oven 11 of any well known structure comprises a plurality of walls 12 composed of heat insulating material that enclose a heating chamber (not shown). A door 13 is located in, and pivotally supported by, one of the walls 12 in such manner that it may swing outwardly and downwardly from said wall about a pivotal support 14 that is attached to wall 12 in any well known manner by brackets 15 and 16. A coil spring 17 is secured to the door 13 and pivot member 14 and it serves to automatically return the door 13 to its closed operating position. Two latches 18 and 19 of any well known structure are actuated by handle 21 in the usual manner to permit opening of door 13 and the locking thereof in closed operating position.

In one of the walls 12, preferably that which includes door 13, a portion of the wall 12 is broken away to provide an opening 22

therethrough that is enclosed by transparent members 23 and 24. The transparent members 23 and 24 are composed of material that retains its form and transparency under the effects of heat and are secured to wall 12 by bolts 25 and 26.

A metallic casing 27 is secured to the wall 12 by bolts 26 and is located over the opening 22 in such manner that it completely covers the same, an opening on the interior surface of the casing being provided whereby the interior of the casing is in direct communication with the opening 22 in the wall 12.

A lamp 28 is disposed within the casing 27 and secured to the bottom thereof in any suitable manner. In the preferred embodiment, an insulating base member 29 is secured by bolts 30 to the casing 27 and the lamp socket is mounted thereon. Conductors 31 and 32 are connected to a source of current (not shown) one conductor 31 being connected to the lamp 28 as at 33. Conductor 32 is connected to a terminal member 34 of a spring switch member 35. The spring switch 35 is arranged, when actuated in a manner hereinafter more fully described, to make a contact with terminal member 36 that is connected by conductor 37 to the remaining lamp terminal 38, thereby connecting the lamp 28 in circuit with the source of electrical current. Contactor members 34 and 36 are supported in any well known manner on an insulator member 40, that is secured to insulating member 29 in the usual way, by bolts 39 and 41.

An insulating tip member 42 is secured by a pin 43 to the rectangularly bent lever 44 that is pivotally supported by bolt 45 and fixed to wall 12 by bracket 46. Spring 47 engages insulating tip member 42 and normally urges a pivotal movement of lever 44 about pivot 45 to engage the spring switch 35 and force it into contact with contactor 36.

A projection 48 of door 13 engages an extension 49 of lever 44 when the door is in its closed operating position. In this position, lever 44 is so pivoted about pivot 45 that insulating tip member 42 compresses spring 47 and is withdrawn from spring switch 35 thereby interrupting the electric circuit and preventing flow of current to the lamp. When the door 13 is open the door

projection 48 disengages from lever extension 49 thereby permitting spring 47 to force lever 44 against spring switch 35 which, in turn, contacts with contactor 36 to close the 5 circuit and energizes the lamp 28.

A reflector 51 is mounted in casing 27 in such manner that light from lamp 28 is projected through transparent members 23 and 24 and serves to illuminate the enclosure of 10 the walls 12.

It is obvious that this structure provides a simple and practical means for illuminating the interior of a heating oven and that it is so arranged that the illuminating means 15 is amply protected from heat of the oven, thereby prolonging the life of the illuminating means and ensuring its practical operation.

Various modifications and changes may be 20 made without departing from the spirit and scope of the invention, and I desire therefore that only such limitations shall be placed thereon as are imposed by the prior art or are set forth in the appended claims.

25 I claim as my invention:

1. In an electrically heated device, the combination with, an oven member comprising a plurality of wall members enclosing an oven chamber having a door member associated with one of said wall members and having an opening in said wall adjacent said door, of electric illuminating means associated with said opening comprising an electric light bulb, switching means therefor 35 normally biased to the open position for de-energizing said lamp and pivotally mounted means adapted to engage the door when said door is closed and so biased as to hold said switching means closed when said door is 40 open.

2. An illuminating means for an oven member, having a pivotally mounted door in one wall thereof and an aperture in said wall adjacent said door, comprising a member of box shape mounted over said aperture, having a light bulb mounted on an insulating base therein and a switch for said light bulb adjacent thereto mounted on a second insulating base, said switch being biased to the open position, a reflector so mounted as to 45 direct the light from said bulb through the aperture, and a pivotally mounted member so biased as to engage and to hold the switch closed when the door is open and to engage the door when said door is closed thereby 50 permitting the switch to return to said biased position.

3. An illuminating means for an oven member, having a pivotally mounted door in one wall thereof and an aperture in said 55 wall adjacent said door, comprising a member of box shape mounted over said aperture, having a light bulb mounted on an insulating base thereon, a switch for said light bulb adjacent thereto, mounted on a second 60 insulating base, said switch being biased to the open position, a reflector so mounted as to direct the light from said bulb through the aperture and a pivotally mounted member of substantially L-shape, having an insulating block on one leg thereof that engages said switch, so biased as to engage and to hold the switch closed when the door is 65 open and to engage the door when said door is closed thereby permitting the switch to 70 return to said biased position.

In testimony whereof, I have hereunto 75 subscribed my name this 27th day of May 1924.

JAMES C. WOODSON.
